ALVA A. EVANS, OF ANNONA, TEXAS.

AUTOMATIC TRAIN-STOPPING MECHANISM.

1,349,504.

Specification of Letters Patent. Patented Aug. 10, 1920.

Application filed August 15, 1919. Serial No. 317,736.

To all whom it may concern:

Be it known that I, ALVA A. EVANS, a citizen of the United States, residing at Annona, in the county of Red River and State 5 of Texas, have invented new and useful Improvements in Automatic Train-Stopping Mechanism, of which the following is a specification.

The object of my present invention is the 10 provision of a purely mechanical, automatic train-stopping mechanism, and one that is simple and inexpensive in construction, susceptible of ready installation, and reliable in operation.

15 To the attainment of the foregoing the invention consists in the peculiar and advantageous train-stopping mechanism hereinafter described and definitely claimed.

In the accompanying drawings, hereby 20 made a part hereof:

Figure 1 is a view, diagrammatic in character, and showing the best practical embodiment of my invention of which I am cognizant.

25 Fig. 2 is an enlarged detail view showing the means for locking the throttle lever and the air-valve lever in open position following an operation of the mechanism.

Fig. 3 is a detail section showing the 30 connection of the forward end of the longitudinal, downwardly-bowed spring.

Fig. 4 is an enlarged detail section showing the cylinders and the parts complementary thereto.

35 Similar numerals of reference designate corresponding parts in all of the views of the drawings.

The major portion of my improvement is 40 designed to be carried upon a locomotive 1, and among other elements the mechanism comprises a longitudinal downwardly bowed spring 2, that is connected at its rear end to a hanger 3 on the locomotive, and has a longitudinal slot 4 adjacent to its 45 forward end for the reception of a bolt 5 carried in a hanger 6 that depends from one of the drive boxes of the locomotive or from any other suitable part thereof. Manifestly the provision just described enables the forward 50 end of the spring 2 to move forwardly when the intermediate portion of the spring is pressed upwardly, and in that way contributes to the reliability of the organized mechanism. At 7 and 8 are supplemental 55 springs interposed between intermediate portions of the bowed spring 2 and a locomotive

part 9 above spring 2 and having for their function to assist the upward movement of the intermediate spring portion, and in that way contribute to the 60 prompt operation of the mechanism under certain conditions, as hereinafter set forth. Carried at the side of the locomotive is an upright guide tube 10, and extending through and adapted to play in said tube 65 is an upright rod 11, the lower end of which is connected to the spring 2. At its upper end the rod 11 is connected to a ratchet bar 12, and the said bar 12 is connected, in turn, with an upright retractile spring 13, the 70 upper end of which is connected to the upper portion of the locomotive cab 14, or to any other suitable support provided at the proper point. The said spring 13 is provided to assist in prompt upward movement of the rod 11 and ratchet bar 12, following upward movement of the bowed 75 spring 2. In conjunction with the ratchet bar 12, is provided a spring-pressed dog 15 which has for its function to effectively prevent accidental downward movement of the 80 rod 11 after the said rod is forced upwardly by action against the under side of the spring 2. It will be readily understood that after an operation of my novel mechanism, the dog 15 is manually disengaged from the rear bar 12 to permit of downward movement of said rod 11 under the tension 85 of the spring 2.

Provided on the locomotive in about the 90 relative arrangement illustrated, are longitudinally disposed horizontal cylinders 16 and 17, each of which is preferably, though not necessarily, provided adjacent to its rear end with a pet cock 18. At 19 is the throttle 95 lever of the locomotive, and at 20 is the lever of the engineer's valve complementary to a fluid-pressure brake system. Movable in the cylinder 16 is a piston 21, the rod 22 of which is carried through a guide 23 and 100 is connected to the throttle valve lever 19, while movable in the cylinder 17 is a piston 24 having a rod 25, disposed in a guide 26 and connected with the valve lever 20. Intermediate of a suitable point in the steam 105 generator of the locomotive and the forward portions of the cylinders 16 and 17, is a conduit 30 in which is a valve 31, having a lever 32 that is connected to the rod 11 and is also connected to a retractile spring 33, said 110 spring 33 being connected at its upper end to a bracket 34, and being designed to assist

in the prompt opening of the valve 31 incidental to upward movement of the rod 11. The rods 22 and 25 are preferably formed of sections hinged together at 25°.

5 It will be apparent from the foregoing that upon upward movement of the intermediate portion of the bowed spring 2, the rod 11 will be thrust upwardly and will be automatically locked in raised position, and 10 that the upward movement of the said rod 11 will be attended by opening of the valve 31 and the retention of the valve in open position, with the result that steam will be let into the cylinders 16 and 17 to move said 15 pistons forwardly and to operate the valves 19 and 20, which operation will bring about the stopping of the train.

To release my novel mechanism after an 20 operation thereof, it is simply necessary for the engineer to disengage the dog 15 from the ratchet bar 12, whereupon the spring 2 will overcome the other springs and will, in moving the rod 11 downwardly, close the valve 31, whereby by manual adjustment of 25 the levers 19 and 20, the engineer can close the throttle and air valve and properly position the pistons in the cylinders 16 and 17 in readiness for a subsequent operation.

The spring 2 is arranged to move along 30 at one side of a railway rail 40, and my invention contemplates the placing at the side

of the rail 40 of a tappet 41; the said tappet being adapted to be positioned by a section-foreman or other person having authority to stop a train in an emergency. Manifestly 35 when the bowed spring 2 is carried over and is pressed upwardly by the said tappet 41, the operation herebefore described will be brought about.

Having described my invention, what I 40 claim and desire to secure by Letters-Patent is:

An automatic train - stop mechanism adapted to be carried by a locomotive and comprising in combination with the locomotive and the throttle lever and engineer's valve thereof, a longitudinal downwardly bowed spring, one end of which is movable longitudinally, a rod connected to and extending upwardly from the bowed spring, 50 a ratchet bar connected to the upper end of said rod, a dog for preventing casual downward movement of the ratchet bar, longitudinally disposed cylinders, a conduit intermediate of a source of steam supply 55 and the cylinders and having a rocking valve on which is a lever loosely and directly connected with said rod, and pistons disposed in said cylinders and connected with the throttle lever and the valve lever. 60

In testimony whereof I affix my signature.
ALVA A. EVANS.
